DESIGN FOR A BRASSIÈRE OR SIMILAR GARMENT

Louis J. A. Amyot, Quebec, Quebec, Canada

Application January 28, 1941, Serial No. 98,467
In Canada January 9, 1941

Term of patent 7 years

To all whom it may concern:

Be it known that I, Louis J. A. Amyot, a subject of the King of Great Britain and resident of the city of Quebec, in the Province of Quebec, and Dominion of Canada, have invented a new, original, and ornamental Design for a Brassière or Similar Garment, of which the following is a specification, reference being had to the accompanying drawing, forming part thereof.

In the accompanying drawing:

I claim:

The ornamental design for a brassière or similar garment, as shown.

LOUIS J. A. AMYOT.
